UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

PULL-SWITCH INDICATOR.

1,249,065.

Specification of Letters Patent. Patented Dec. 4, 1917.

Application filed April 9, 1914. Serial No. 830,819.

To all whom it may concern:

Be it known that I, GILBERT W. GOODRIDGE, a citizen of the United States of America, and residing at Bridgeport, in the county of Fairfield and State of Connecticut, have invented a certain new and useful Improvement in Pull-Switch Indicators, of which the following is a specification.

My invention relates to switch indicators and particularly to indicators for pull switches, the object of my invention being to provide a simple and inexpensive device for this purpose particularly adapted for use with switch mechanisms of the type herein-
after described.

In the accompanying drawings,

Figure 1 is a vertical section through an electric lamp socket of the pull type in which an indicator embodying my invention is embodied;

Figs. 2 and 3 are horizontal sections through the socket showing the switch mechanism in two different positions; and

Fig. 4 is a perspective of a modified detail.
In certain pull switches, the operating mechanism is of such character that the pull member, ordinarily a flexible pull chain of the ball and link type, takes different positions *i. e.* is drawn farther in or left farther out in the "on" and "off" positions of the switch. An example of such mechanism is illustrated in the patent to Peet 1,089,785, December 1, 1913 and the construction there shown is employed to illustrate the present invention.

This pull socket comprises the usual cap 10 and shell 11 forming a casing with insulating lining 12 to inclose the switch mechanism arranged between the insulating buttons 13 and 14 and the socket shell 15 mounted on the latter. The switch mechanism is described in detail in the patent above referred to, and it suffices for the explanation of the present invention, to point out that the switch piece 16 lies in the "off" position in Fig. 2 and in the "on" position in contact with terminal 17 in Fig. 3. The movement of the switch piece is effected through a spring 18 one end of which is fast to the switch piece and the other end of which is fast to a yoke 19 pivoted on the switch spindle 20. The pull member or chain 21 engages the outer end of the yoke 19 and passes out through the bell 22 beyond which point it is grasped by the operator. In the

"off" position of the switch the yoke 19 is carried by the joint action of the switch spring 18 and the return spring 23, to the tension of which the yoke is also subjected, to the position shown in Fig. 2, viz., to the 60 point at which it is halted by the impingement thereof, or of the end ball of the chain, against a stop such as the standard 24 which spaces the buttons 13 and 14 apart. In the "on" position of the switch however, the 65 yoke 19 is halted about midway of its arc of travel by the stop shoulder 25 engaged by the trigger 26 carried by the yoke 19 as explained by the above mentioned patent. It is thus apparent that in the "on" position 70 of the switch the pull chain hangs farther out of the socket than in the "off" position of the switch.

This in or out position of the chain affords ready means for indicating the position of 75 the switch. Thus an enlarged ball 27 may be mounted in or on the chain, preferably at the bell mouth, so that when the switch is "off" this ball 27 is drawn up into the bell, whereas when the switch is "on" it hangs 80 clear below it, as indicated in dotted lines Fig. 1. The operator can tell at once by the position of the ball in what position the switch lies.

If a more explicit indication is desired, 85 the ball may be replaced by an indicator such as that illustrated in Fig. 4. This comprises a blank struck to shape and having flat faces 28 and 29 adapted to receive the words "on" and "off". Lugs 30 may be ex- 90 tended from one face to rest upon the bell mouth and hold the indicator in proper position, while the metal between the lugs may be turned in to form a spring socket 31 through which one of the chain balls may 95 be snapped to fasten the device on the chain. As the chain is drawn in, the indicator is pulled up into the bell mouth and displays face 29 bearing the word "off". When the chain hangs out in the "on" position of the 100 switch, the face 28 bearing the legend "on" is displayed.

Various other devices will readily suggest themselves and I do not limit my invention to the details described.

I claim as my invention:—

1. In a pull switch, a flexible pull member having in and out positions respectively in the "on" and "off" positions of the switch, and an indicator on said pull member serv- 110

ing by its different positions to indicate the position of the switch.

2. In a pull switch, a bell mouth chain guide, a flexible pull member passing through said bell mouth and having in and out positions respectively in the "on" and "off" positions of the switch, in combination with a self-contained indicator carried by the chain at the bell mouth and serving by 10 its in or out position to show the "on" or "off" position of the switch.

3. A pull switch having a bell mouth chain guide, a pull chain passing therethrough and an indicator on the chain bearing 15 against the said guide and moving over the same into different positions in the "on" or "off" condition of the switch, whereby said condition is indicated, substantially as described.

4. In a pull switch, a flexible pull member having in and out positions respectively in 20

the "on" and "off" positions of the switch, and an indicator member of greater diameter than the pull member and mounted on the latter, said indicator serving by its different positions to show the position of the switch. 25

5. In a pull switch, a flexible pull member having in and out positions respectively in the "on" and "off" positions of the switch, 30 and an indicator mounted on the pull member, and having different angular positions in the respective positions of the latter, and having means for indicating in said different positions the condition of the switch. 35

In testimony whereof I have signed my name to this specification, in the presence of two subscribing witnesses.

GILBERT W. GOODRIDGE.
